Specification of Letters Patent.

Patented Dec. 28, 1915.

Application filed October 15, 1913. Serial No. 795,231.

To all whom it may concern:

Be it known that I, CHARLES A. NELSON, a citizen of the United States, residing at Utica, in the county of Oneida and State 5 of New York, have invented certain new and useful Improvements in Firearms, of which the following is a specification.

This invention relates to guns of the automatic type, that is to say, guns in which 10 the operation of extracting the spent shell, cocking the piece and introducing a fresh cartridge are accomplished through the recoil of the gun, and it has for its object to provide a gun of this class with an improved means, requiring no movable part, for controlling the opening of the breech upon explosion of the charge with a view 15 to prevent dangerous release at the breech of the powder gases.

20 My invention is dependent upon the known circumstance that on explosion of a cartridge the cylindrical wall of its shell expands; and it consists in providing the cartridge chamber of the gun with a novel 25 means for setting up resistance to the backward movement of the shell upon the explosion of the cartridge and the consequent expansion of the shell.

I have illustrated my invention in the accompanying drawings, Figure 1 showing a gun, having my improvements, in longitudinal vertical section; Fig. 2 showing the frame, the barrel, and breech-closing element, the breech part of the barrel appearing partly in section; Figs. 3 and 4 being enlarged vertical sectional views on the lines $x-x$ and $y-y$ of Fig. 2, respectively; and, Fig. 5 a view of the front end of the breech-closure when formed in furtherance of my 40 invention.

In the drawings, a is the frame; b the barrel fixed in the barrel abutment c ; d and e the breech-block and breech-bolt, respectively, of the breech-slide or breech-closing element; f the spring normally holding the breech-slide with its breech-bolt in closing relation to the rearwardly open cartridge chamber g provided in the breech or rear end of the barrel, being therefore adapted, upon the breech slide being forced back upon explosion of a cartridge in the breech to a limit afforded by contact of the block at h with the barrel abutment, to return the breech 50 slide in the usual way; i is the firing pin, 55

housed in the bolt and normally pressed forward therein so as to protrude and impinge upon the cartridge by the spring-driver j ; k the sear fulcrumed at l between its ends and held with its rear end in dogging relation to the firing pin by the spring device m ; n the trigger and o the trigger pawl for transmitting to the sear the sear releasing movement of the trigger.

Describing that species of my invention shown in the drawings, the cartridge chamber g , which appears in Fig. 2 as extending from the abutment shoulder p for the forward edge of the cartridge-shell rearwardly to the breech end of the barrel has a cartridge-shell-gripping surface-portion extending around its longitudinal axis that is provided with laterally facing shoulders—in the present case, afforded by spiral ribs, corrugations or scorings q —and presents an approximately straight profile in any section of said surface-portion that is substantially parallel with said shoulders. Upon explosion of a cartridge in a chamber thus formed (it being assumed that the cartridge is related to the scored surface-portion of the chamber with substantially the same snugness of fit as it would be if said surface-portion were that of a cylinder represented by the inner apices of the scorings) and consequent expansion of the cylindrical wall of the shell against the scorings, resistance to the rearward movement of the shell of a dual character is set up. Thus, first, there is the resistance due to the expansion of the shell outwardly against the scorings, and hence into more or less extended contact with the laterally facing shoulders they afford, and lasting only so long as the instant that the pressure is effective to maintain such expansion (that is to say, assuming that the shell will contract upon cessation of the pressure sufficiently to practically eliminate the friction between the shell and the chamber, as it usually will, it being understood that if it did not contract so as to eliminate friction between it and the chamber, such resistance, though reduced, would last until the shell rearwardly cleared the chamber); and, second, there is also the resistance afforded by the fact that the shoulders are spiral and that the relatively forward one in each instance therefore more or less obstructs the rearward movement of the shell, this resistance 100 105 110 115

usually lasting after the pressure ceases to act on the shell, that is, lasting until the shell rearwardly clears the shoulders. Though both of these forms of resistance exist in that adaptation of my invention herein shown, it will be understood that either may be resorted to without the other.

After the pressure has expended itself the force operative to drive the shell and hence 10 the breech-block to the rearward limit (fully opening the breech) is the unexpended energy or "force of recoil" left stored in the shell and breech-closing element.

Where the scorings are so formed as to 15 require rotary movement of the shell in order to clear the chamber rearwardly, resistance to such rotary movement of the shell may be set up (thus further opposing its rearward movement) by forming the 20 breech-closing element with impress-forming means. Thus the breech-bolt *e* is shown as provided with the radial scorings *s* on its acting face, the effect of which will be to produce impresses in the rear face of 25 the cartridge shell, the shoulder forming one side on each scoring and the coacting surface of the corresponding impress coacting with each other to resist rotation of the shell (Fig. 5).

30 The smooth surface portion *r* serves, in coöperation with the portion of the shell embraced thereby, to form a seal preventing the backward release of the powder gases through the channels or grooves 35 formed between the scorings.

Having thus fully described my invention, what I claim as new and desire to secure by Letters Patent is:—

1. A gun of the blow-back type including, 40 with a cartridge-chamber-forming structure having its chamber open rearwardly, a chamber-closing element movable rearwardly in response to explosion-pressure to open said chamber, said chamber having 45 means to resist the backward movement of the cartridge on explosion and thereby delay the backward movement of said element consisting in a cartridge-shell-gripping surface-portion extending around the longitudinal axis of said chamber and provided with a laterally facing shoulder or shoulders and presenting an approximately straight profile in any section of said surface-portion that is parallel with said shoulder or shoulders.

50 2. A gun of the blow-back type including, with a cartridge-chamber-forming structure having its chamber open rearwardly, a

chamber-closing element movable rearwardly in response to explosion-pressure to 60 open said chamber, said chamber having means to resist the backward movement of the cartridge on explosion and thereby delay the backward movement of said element consisting in a cartridge-shell-gripping surface-portion extending around the longitudinal axis of said chamber and provided with a spiral laterally facing shoulder or shoulders and presenting an approximately straight profile in any section of said surface-portion that is parallel with said shoulder or shoulders.

3. A gun of the blow-back type including, with a cartridge-chamber-forming structure having its chamber open rearwardly, a 75 chamber-closing element movable rearwardly in response to explosion-pressure to open said chamber, said chamber having means to resist the backward movement of the cartridge on explosion and thereby delay the backward movement of said element consisting in a cartridge-shell-gripping surface-portion extending around the longitudinal axis of said chamber and provided with a laterally facing shoulder or 80 shoulders and presenting an approximately straight profile in any section of said surface-portion that is parallel with said shoulder or shoulders, said chamber also having another and smooth cartridge-shell-gripping surface-portion coactive with a part of 85 the shell to form a continuous seal.

4. An automatic gun including, with a cartridge-chamber structure having its chamber open rearwardly and formed with 95 means to impart rotary movement to the cartridge shell upon rearward movement thereof, a chamber-closing element having means to obstruct such rotary movement of the shell.

100 5. An automatic gun including, with a cartridge-chamber-forming structure having its chamber open rearwardly and formed with means to impart rotary movement to the cartridge shell upon rearward movement thereof, a chamber-closing element having a crosswise shoulder or shoulders to interlock with shoulders on the rear face of the shell.

105 In testimony whereof I affix my signature 110 in presence of two witnesses.

CHARLES A. NELSON.
